UNITED STATES PATENT OFFICE.

JULIUS H. GILLIS, OF ELIZABETH, NEW JERSEY, ASSIGNOR, BY MESNE ASSIGNMENTS,
TO ANACONDA SALES COMPANY, A CORPORATION OF DELAWARE.METHOD AND APPARATUS FOR CONTINUOUSLY COATING ROOFING ELEMENTS
ELECTROLYTICALLY.

Application filed August 15, 1923. Serial No. 657,482.

To all whom it may concern:

Be it known that I, JULIUS H. GILLIS, a citizen of the United States, residing at Elizabeth, in the county of Union, State of New Jersey, have invented certain new and useful Improvements in Methods and Apparatus for Continuously Coating Roofing Elements Electrolytically; and I do hereby declare the following to be a full, clear, and exact description of the invention, such as will enable others skilled in the art to which it appertains to make and use the same.

This invention relates to a method and apparatus for continuous coating of roofing elements electrolytically, and more especially, to the coating of roofing elements formed of a heat-insulating material provided with a metallic protective layer over the weather surface, the object of the invention being to provide an improved method and apparatus for continuously applying this protective layer.

The roofing elements within the contemplation of this invention may be in the form of boards, strips, shingles, tiles, and the like, and the body or base of these elements is made of various materials having heat-insulating qualities. For this purpose, impregnated felt and asbestos products, the so-called asphalt shingles, magnesite compositions, and many similar heat-insulating, heat-resistant, and non-deteriorating materials may be used.

Such a base may be made peculiarly durable, as well as given a distinctive and attractive appearance, by coating the surface area to be exposed to the weather, with a non-corrodible metal, such as copper. With a metallic coating of this kind, the roofing element combines the long life of a metal roofing with the heat-insulating properties of the materials of the base.

Metal roofing in the form of sheets, strips, etc. is quite satisfactory as to durability, but it transmits heat so rapidly as to necessitate the use of some sort of an insulating sheathing beneath it. Roofing elements of the specified materials, without the protective weather surface, fulfill the requirements as to heat-insulation, but are not altogether durable and are not as agreeable

to the eye as the metal. The roofing elements produced by my improved method combine the good qualities of each kind of roofing.

In my prior application, Serial No. 625, 286 filed March 15, 1923, there is described a method and apparatus for applying the metallic protective layer to roofing elements in a continuous series, the elements being successively passed through the various steps of the process and acted upon by the apparatus to produce the finished articles.

That process has proved successful in applying a uniform metallic coating to the roofing elements. However, experience has shown wherein certain improvements could be made and the present invention is intended to improve certain steps of that process, particularly the step of electrolytically depositing the metallic coating, as well as the apparatus for carrying on the improved process.

In carrying out my former process, the roofing elements were first clamped in individual holders which were connected together by means of links so that a plurality of these individual holders could be drawn through the electrolytical cell in a continuous series. A plurality of anodes were arranged within an electrolytic cell above the holders containing the roofing elements and the holders in a continuous series were advanced by a step by step movement so as to carry the elements forward a distance sufficient to bring an element of the series under the next succeeding anode at each step. In order to collect the plating current from the surface of the elements to which a conductive coating of graphite, lead, or similar material, had previously been applied, a single electrical conductor was imbedded in one clamping face of the holders so as to contact with the conductive layer.

In this prior process, therefore, it is necessary to insert the individual roofing elements in the holders by hand, and it is preferable, in order to secure uniform plating and minimum consumption of electric energy, to advance the elements through the cell by a step-by-step movement.

Whenever a conductive layer of some

such material as graphite or lead has been applied to a non-conducting base for the purpose of applying a metallic coating electrolytically, it has been necessary heretofore to take certain precautions in order to secure an even deposition of the metal, because slight variations in the thickness of the conductive layer will cause such variations in the electrical resistance of this layer 10 as will result in uneven deposition. In my prior process, therefore, it is necessary to use considerable care in applying the conductive layer to make it uniform.

Furthermore, by collecting the plating current from the conducting layer along one margin thereof, the metallic coating has a tendency to build up thicker in the region near this margin because of the greater 20 electrical resistance of the current path to the more remote points toward the edge of the element, and the anodes must be properly spaced in relation to the elements to counteract this tendency.

My present invention provides for moving the elements through the electrolytic cell with a uniform continuous motion while securing a uniform deposit of metal without any substantial increase in the electric 25 energy required. It further provides for the continuous movement of the points where plating current is withdrawn from the conductive layer with respect to the surface of this layer so that the distance which the current must travel through the 30 conductive layer is always continuously varying and is always limited to a relatively small distance.

A series of electrical conductors, which 40 also preferably constitute supports for the roofing elements, are disposed throughout the length of the electrolytic cell, the anodes being laid beneath these conductor-supports. The roofing elements are themselves connected together by any flexible means to 45 form a chain, and are drawn over this series of conductor-supports with their conductive coatings face down and in contact therewith. Thus, the necessity for the use of the 50 holders or clamps is disposed with and this effects a saving both in the cost of installation and operation of the apparatus. Since the anodes are below the roofing elements, rather than above them, anodes of crude copper 55 may be used inasmuch as the slimes resulting from the solution of the anodes will now settle on the anodes and can be easily withdrawn, whereas in the earlier process the slimes settled upon the elements themselves and were likely to be carried out of the cell 60 with the elements.

To make clear the practice of this present process and to illustrate one form of apparatus to be used for such purpose I shall refer to the accompanying drawings. In 65 these drawings:

Fig. 1 is a diagrammatic plan view of the layout of the apparatus by which the several steps are performed, including the steps of the complete process described in my prior application above mentioned. 70

Fig. 2 is a diagrammatic plan view showing the positions of the roofing elements at the different stages in their travel through the apparatus.

Fig. 3 is a diagrammatic view in side 75 elevation showing the relative positions of the various elements in the chain during the progress of these elements through the apparatus.

Fig. 4 is a view in vertical cross section 80 of that part of the apparatus in which the deposition takes place.

Fig. 5 is an inclined plan view taken on the line 5-5 of Fig. 4, and showing the 85 grid lay-out.

Fig. 6 is a plan view showing the wall of one of the compartments and illustrating the relative positions of the grids and anodes and the electrical connections therefor.

Figs. 7 and 8 are plan views of modified 90 forms of grid.

Fig. 9 is a longitudinal cross-section of one of the grids shown in Fig. 5.

Fig. 10 is a detailed perspective view of 95 a portion of a grid cross-bar of the type illustrated in Fig. 8.

Fig. 11 is a detailed view in vertical cross-section of one compartment of the deposition apparatus showing a pressure device 100 installed therein, and

Fig. 12 is a view similar to Fig. 11 for showing a modified form of device.

In the drawings, and with reference particularly to Fig. 1, there is shown a conveyor 9 which brings the elements from the source of supply to the electrolytic apparatus. These elements are preferably connected in a continuous chain during the process of formation, and the connections between individual circuits of the chain may consist of fine copper wire or other flexible material of that character. These connecting links should be of sufficient strength to bear the strain of pulling a chain of elements through the electrolytic compartments, but a chain formed of a series of elements, the adjacent units of which are connected together by three strands of light copper wire, will be sufficiently strong for this purpose. This connecting of the units 110 in a chain not only dispenses with the 115 holders which were described in my previous application above referred to, but the arrangement makes it more convenient to handle the units when they are to be shipped, and also to be laid in place on the roof. From the 120 conveyor 9 the chain of elements passes three stations designated as 10, 11 and 12. At the first of these there is applied to the 125 weather surface of each unit a suitable ad-

130

hesive, this material being sprayed on or otherwise conveniently applied. At station 11 a conducting material is applied over the surface of the element previously 5 coated with adhesive, and at the station 12 these coatings are dried, as for instance, by passing the elements through a heated chamber. The purpose of applying the conducting material is, of course, to permit the 10 electrolytic deposition of the coating layer over the surface of the element which is normally an insulator. The method of applying this conducting coating may be varied, however, in accordance with the particular needs of the type of element which 15 is to be treated. Also the drying process which may be carried out by means of a hot air chamber may be dispensed with by employing a quick drying adhesive, so that the conducting material will be firmly held in place by the time the chain of elements has reached the cell in which the deposition 20 is to take place. This cell is designated generally by the reference character 13 and 25 is shown in detail in Fig. 4.

A convenient arrangement of the apparatus will include the mounting of a plurality of deposition compartments or troughs of a single upright standard. This standard 30 is designated as 14, and is in the form of a partition which runs throughout the apparatus. This partition may be made of any suitable material which has the rigidity and strength to support the series of troughs 35 now to be described. Disposed along either face of these partitions is a series of triangular spacing bars 15 and mounted on the upper inclined surface of each of these bars is a trough 16. As shown in Fig. 4 each 40 trough is made of three walls 17, 18 and 19. These walls extend throughout the length of the cell. The outer wall 17 is disposed at an angle to the central partition and extends outwardly for a distance slightly 45 greater than the length of a roofing element. The wall 18 is at right angles to the wall 17 and rests against the spacing bar 15 while the short wall 19 bears against the lower face of the spacing bar next above that which supports the trough. These 50 three walls which form the trough are ordinarily made of wood and are provided with a protective sheathing 20 on their inner surfaces so as to protect the wood from the electrolyte. Other materials such as 55 slate, or any such material which would not be affected by the electrolyte may also be used, but it is less expensive to make use of sheathed wood in the manner described.

These troughs formed of the three walls extend throughout the length of the central partition and at spaced intervals along the outer edge of the wall 17, are bus bars 21 illustrated more clearly in Fig. 6, resting on 60 suitable supporting ledges 22. Opposite

each of these bus bars is an anode 23 which may be formed of crude copper cast in the shape of a flat plate. Each anode, however, has an offset connecting member or terminal 24 which overlies and bears against the 70 appropriate bus bar. Each anode is of a length substantially equal to two units in the chain of elements and successive anodes as shown in Fig. 5 are spaced apart by a distance greater than the width of a unit. This 75 is for a purpose which will be later made clear.

Mounted on suitable supports 25 in a position overlying each of the anodes is a grid 26. These grids are formed of conducting 80 material and consist of a pair of side bars 27, 27 between which is disposed a series of cross arms 28 which are inclined transversely in the direction of movement of the elements through the cell. As shown in 85 Fig. 4 the series of grids is spaced parallel with the outer wall 17 of the cell, and lies but a short distance from the upper face of the anode. The side and cross bars 27, 28 are made of a conducting material, pref- 90 erably metal but are partially encased in an insulating coating so that only a small portion of their upper surfaces is exposed. This arrangement is illustrated in Fig. 9, in 95 which the insulating coating is designated as 28'. The grids of this construction are spaced apart by a distance corresponding to the interval between successive anodes and each grid is connected by a conductor 29 to the anode next preceding it. According- 100 ly in any single compartment or trough of the cell the grids and anodes are connected electrically in series. Other electrical connections by which two or more anodes are arranged in parallel may also be employed.

The electrical connections which are used will depend on the conditions under which the electro-deposition is to take place and will also depend to some extent on the character of the source of current which is available. The rate of deposition and the character of the deposition are controlled by the electrolytic conditions in the cell and such conditions will be established as are most conducive to the production of a plated 110 shingle of the desired character.

As has been explained, the elements pass through the cell in a series such as is illustrated in Fig. 2. The weather surface 30 of each element has been coated with adhesive and in turn has had a layer of conducting material applied to it. A chain of such elements is then introduced into each trough or compartment of the cell, each of 115 these troughs being partially filled with electrolyte as indicated at 31. This chain of elements is placed above and rests against the series of grids and when the current is turned on deposition takes place from the 120 anodes upon the conducting surfaces of each 125 130

element which has been laid so that it faces the anodes. It will be apparent from Fig. 4 that the surface on which the metal is to be deposited is only a short distance from the face of the anodes, and as the chain of elements move along deposition will take place uniformly over the conducting surface of the element, since the grid cross bars do not continuously mask any part of this surface.

The current passes into the cell from the first anode in the series across the liquid to the conducting surface on the first element which forms the cathode, thence to the nearest cross bar of the grid, thence through the conductor 29 to the next anode where the passage across the liquid is repeated. It is possible that some deposition will take place on the exposed portion of the cross bar of the grid, but such deposited metal will be removed by the continual wearing action of the chain of elements passing over these cross bars. Accordingly the cross bars do not build up to such an extent as to interfere with the deposition. It is preferable that successive anodes and their corresponding grids should be spaced apart a distance somewhat greater than the width of an element of the chain since otherwise there is likely to be set up countercurrents within the cell which might cause a portion of the plated material to go into solution.

I have found that the spacing of the cross bars of the grids and their angular inclination serves a useful purpose in improving the quality of the deposit. It will be noted that as the elements move over the grids the plating current at any instant must flow from a particular point in the coating on the elements to the nearest cross bar, thence to the end bar of the grid from where it passes on to the next anode. As the elements move along over the grids the inclined position of the cross bars insures that no portion of the surface of the element will be masked and thereby prevented from being coated. At the same time the distance from any particular point on the element to the nearest cross bar will vary continuously within fixed limits as the element passes along. The elements pass successively over a series of collectors for the plating current and this insures that there will be no blank spots in the coating. I have found that it is better in some instances to make these collectors in the form of a series of spaced points rather than in the form of spaced bars as is illustrated in Fig. 5, and the modified form is shown in Figs. 8 and 9.

In this arrangement the grid construction is similar to that previously described but the surfaces of the cross bars 28 are insulated save at certain exposed points indicated at 32. In successive grids these exposed points will be in staggered relationship as indicated

at 33. The purpose of using point collectors is to insure proper contact of these points with the conducting coating on the elements. It sometimes happens that an element will be slightly warped or distorted so that it will not be perfectly flat so as to make good contact with the grid collector bars. However, by providing point collectors as shown in Fig. 8, these collectors provide a distributed point support for the elements which will insure that these points will always be in contact with the conducting coating. By having the points on successive grids in staggered relationship it is possible to insure that the distance from any given point on an element to the nearest point of collection will not vary beyond certain small limits, and this makes certain that in the passage of each element throughout the length of the cell the deposited coating will be uniform in quality and thickness.

In order to insure a more nearly perfect contact between the conducting surface of any element and the grids over which it passes, it is sometimes desirable to provide pressing devices such as are illustrated in Figs. 11 and 12. In Fig. 11 I have illustrated the use of a roller 34, preferably a rubber roller or a roller with a rubber surface, which is supported in a stirrup 35 mounted on the under side of a compartment wall 17. Each compartment wall is provided with a series of rollers, each of which is spaced so as to overlie one of the cross bars of the grids. These rollers may be adjustably secured in the position and serve to exert a yielding pressure on the upper surface of the elements so as to cause the conducting surface to bear with a light pressure against the cross bar of the grid. It is desirable that the roller should lie above the surface of the electrolyte in the compartment and it is also desirable that the roller and its supporting parts should be formed of material which is not affected by the electrolyte. In Fig. 12 the pressure roller is of a somewhat modified construction, being supported rotatably on the end of an arm 36 pivoted at 37 to the under surface of the compartment wall and held with a yielding pressure against the elements in the compartment below by means of a spring 38. Either of these types of pressing roller may be used successfully and in case the grid is of the form illustrated in Fig. 5 the roller will be located so as to bear against the element at a point opposite the center of the conducting surface. In case grids of the form illustrated in Fig. 8 are employed it is preferable that the rollers be spaced so as to bear against the element at a point opposite the contact points which, as has been previously described, are in staggered relation to the cross bars of a single grid.

By mounting the anodes in the position shown and lying against the outer wall of the compartments beneath the grids, it is more convenient to remove and replace these anodes when they have been exhausted. Again since each anode is completely supported, it is possible to permit it to dissolve almost entirely before replacement is made. By depositing upon elements supported above the anodes, the latter may be made of crude metal and the slimes which result from the electrolysis will thus collect on the anode and in the bottom of the cell rather than being carried away by the elements themselves and so being removed as the elements pass out of the cell. In many instances the slimes contain valuable ingredients which may be later recovered, and by this arrangement such slimes may be readily collected. The electrolyte, the level of which is indicated at 31 in Fig. 4, is refreshed as may be required, and it is also desirable that the troughs in any particular cell should be connected by suitable passages so that a circulation of the electrolyte may be set up. Frequently these connections will be at opposite ends of adjacent troughs so that the electrolyte will pass the length of one trough into the trough next below, flowing through the length of that trough and then into the trough beneath, this zigzag travel being repeated until the liquid is to be taken out of the lowest trough when it will be pumped or otherwise conveyed to the top trough on the other side of the partition. This circulation will be kept up throughout the time that the deposition is being carried on and quantities of the electrolyte will be periodically withdrawn to be replaced by fresh liquid. The electrolyte may then be treated for the recovery of the slimes and for purification purposes.

As the chain of elements passes along with its slow uniform movement past the anodes a metallic coating is deposited on the conducting surface of each element and the thickness of this coating depends on the various conditions, such as the speed of travel, the density of the current, etc. At the end of the cell the supporting wall has an upward inclination, as shown in Fig. 3 at 39, so that the elements may pass out of the cell without the electrolyte being lost. The elements then pass through a wash tank indicated diagrammatically at 40, then through another tank at 41, where the last traces of electrolyte are neutralized by a weak alkaline solution and where the quality of the deposit may be inspected. Beyond the tank 41 is another tank 42 in which, if desired, the metallic coating may be treated with suitable solutions to vary the color of the deposit. Passing outwardly from the last tank 41 or 42 as the case may be, the elements pass through a pair of rolls 43

slightly inclined so as to overcome the tendency of the chain to creep downwardly. These rolls 43 are driven by any suitable means and grip the series of chains of elements with sufficient force as to pull them through the several tanks and the cell. Passing from the forwarding rolls 43 the elements are folded upon themselves in zig-zag fashion as shown at 44, and when a bundle of elements of sufficient size has been formed the connecting links may be cut and the bundle removed. A conveyor 45 is provided for removing these bundles to the warehouse where they may be stored or packed for shipment.

In Fig. 7 I have illustrated a modified form of grid in which the cross bars 46 are given a reverse curve formation. The action of these collector bars is in many respects similar to that of the bars 28 illustrated in Fig. 5, but this curved formation in many cases improves the contact of the conducting surface on the elements with the cross bar. If the element is not exactly flat in coming from the cutting apparatus any slight tendency to warp may interfere with the action of the collector bar. This reverse curve formation also appears to permit the elements to be moved over the curved grid bars with less resistance and is therefore somewhat less likely to break off or displace particles of the conducting material. This is a matter of considerable importance in view of the fact that the conducting layer is relatively thin and fragile and any chipping or flaking off of this layer would result in the formation of an imperfect metallic coating. The reverse curve shape of the bars illustrated in Fig. 7, appears to give highly satisfactory results in cases where the conducting layer is of a material which must be carefully handled.

It will be seen that in its improved form the electrolytic cell makes it possible to replace anodes more quickly and also to consume these anodes more completely. Furthermore, the deposit is improved since the slimes do not collect on the surface of the elements which are supported above the anodes. The shape of the individual troughs of the cell permits of a thicker layer of electrolyte covering the areas of the elements which are to be coated and this, coupled with the circulation of the electrolyte, insures a more uniform deposit. Inasmuch as the elements are now connected in a chain of sufficient strength to permit them to be pulled through the cell, it is not necessary to employ individual holders for them. This saves an item of considerable expense in the cost of maintenance, and also of operation since it was necessary to mount each element in place in its holder before it was placed in a cell. This arrangement for connecting the elements in a

single chain also makes it more convenient to handle them when the process is finished, since the elements will be shipped in connected, folded strips which will not be severed until ready for use.

I claim:

1. A process of coating roofing elements of the type described which comprises moving a linearly extending series of connected elements through a cell with a substantially uniform continuous motion, and depositing a metallic coating thereon by electrolysis.
2. A process of coating roofing elements of the type described, which comprises moving a series of elements through an electrolytic cell with the surface of the elements on which a deposit is to be made lying substantially in a plane, and depositing a metallic coating on the elements during such movement by electrolysis.
3. A process of coating non-conducting articles which comprises applying a conducting layer to the surface thereof, connecting the articles together, placing the connected articles in an electrolytic cell and depositing a metallic coating on said layer while continuously moving the point or points of collection of the electric current with respect to the surface thereof.
4. A process of coating roofing elements of the type described which comprises moving a linearly extending series of connected elements through an electrolytic cell with the surface to be coated in contact with a plurality of stationary electrical conductors disposed in the path of travel of said elements.
5. A process of coating roofing elements of the type described which comprises moving a linearly extending series of connected elements through an electrolytic cell with the surface to be coated in contact with a plurality of stationary electrical conductors extending across the path of travel of said elements.
6. A process of coating roofing elements of the type described which comprises supporting a series of elements upon a plurality of electrical conductors within an electrolytic cell, the conductors extending transversely of the series of elements, and moving said elements through the cell in such manner that substantially all of the surface of the individual element to be coated comes repeatedly in contact with a conductor.
7. A process of coating roofing elements of the type described which comprises moving a linearly extending series of connected elements, supported on a plurality of spaced electrical conductors, above a series of anodes disposed in spaced relation opposite said conductors, and depositing a metallic coating on said elements during such movement.
8. A process of coating roofing elements of the type described which comprises mov-

ing a series of elements, supported on a series of spaced conducting grids, over a series of anodes disposed opposite said grids, and depositing a metallic coating on said elements during such movement.

9. A process of coating roofing elements of the type described which comprises mounting a series of pairs of grids and anodes in spaced relation in a cell, connecting each grid to the next succeeding anode, moving a series of elements, supported on the grids through the cell and depositing a metallic coating on said elements during such movement.

10. A process of coating roofing elements of the type described which comprises moving a series of elements provided with a conducting coating through an electrolytic cell while supporting these elements on a plurality of spaced electrical conductors above a series of anodes in spaced relation to said conductors and while maintaining the conducting surface of said elements in intimate contact with said conductors and depositing a metallic coating on said elements during such movement.

11. A process of coating roofing elements of the type described which comprises moving a series of elements provided with a conducting coating through an electrolytic cell having a series of anodes disposed therein while supporting the elements on a series of spaced conducting grids having exposed contact points, and while exerting pressure on the elements to force the latter into intimate contact with said points and depositing a metallic coating on said elements during such movement.

12. An apparatus for coating roofing elements of the type described comprising an electrolytic cell having an anode supported therein, a plurality of spaced current collectors disposed so as to support the elements in plating relation to the anode, and means for moving the elements over said collector supports in a direction transverse to the supports so that each portion of the surface to be plated comes repeatedly in contact with a collector.

13. An apparatus for coating roofing elements of the type described comprising an electrolytic cell having a plurality of anodes therein, a plurality of supports disposed above said anodes, and means disposed outside the cell for moving a series of elements through said cell, while resting on said supports.

14. An apparatus for coating roofing elements of the type described comprising an electrolytic cell having a plurality of anodes therein, a plurality of supports of conducting material disposed above said anodes, means for moving a series of elements resting on said supports, past said anodes, and means disposed outside the cell for deposit-

- ing a metallic coating on said elements during such movement.
15. An apparatus for coating roofing elements of the type described comprising an electrolytic cell having inclined side walls, a plurality of spaced anodes lying against one of said walls, a plurality of supports mounted with their supporting surfaces parallel to said side walls, and means disposed outside the cell for moving a series of connected elements, lying on said supports through said cell.
16. An apparatus for coating roofing elements of the type described comprising an electrolytic cell, a plurality of spaced anodes mounted therein, a conducting support mounted opposite each anode in spaced relation thereto, and means for moving a series of elements lying on said supports through said cell.
17. An apparatus for coating roofing elements of the type described comprising an electrolytic cell, a plurality of spaced anodes therein, a grid composed of side and cross bars of conducting material mounted opposite each anode in spaced relation thereto, and means for moving a series of elements lying on said grids through said cell.
18. An apparatus for coating roofing elements of the type described comprising an electrolytic cell, a plurality of spaced anodes therein, a grid, having a plurality of exposed contact points, mounted opposite each anode in spaced relation thereto, and means for moving a series of elements lying on said grids through said cell.
19. An apparatus for coating roofing elements of the type described comprising an electrolytic cell containing a plurality of anodes disposed lengthwise of the cell, means for moving a series of elements through said cell past said anodes, and means for supporting said elements during such movement, said supporting means comprising a series of grids of conducting material, each grid having side bars lying parallel to the path of travel of said elements and cross bars disposed at an angle to this path of travel.
20. An apparatus for coating roofing elements of the type described comprising an electrolytic cell containing a plurality of anodes disposed lengthwise of the cell, means for moving a series of elements through said cell past said anodes, and means for supporting said elements during such movement, said supporting means comprising a series of grids of insulated conducting material having a plurality of spaced exposed collector points thereon.
21. An apparatus for coating roofing elements of the type described comprising an electrolytic cell containing an anode, means for moving a series of elements through said cell past said anode, and a grid to support said elements in relation to said anode, said grid having a plurality of spaced points, contacting with said elements.
22. An apparatus for coating roofing elements of the type described comprising an electrolytic cell containing a series of anodes spaced lengthwise of said cell, means for moving a series of elements through said cell past said anodes, and a plurality of grids disposed in spaced relation to said anodes and serving to support said elements in their movement, each grid having a series of collector points contacting with said elements and connected electrically to the next adjacent anode of the series.
23. An apparatus for coating roofing elements of the class described comprising a coating station, an electrolytic cell, and a washing tank, and means disposed at one end of said apparatus for drawing a series of connected elements therethrough with a uniform movement.
24. An apparatus for coating roofing elements of the class described comprising a coating station, an electrolytic cell and a washing tank, means for drawing a series of connected elements through said apparatus with a uniform movement, and means for supporting said elements in said cell in an inclined position.
25. An apparatus for coating roofing elements of the class described comprising an electrolytic cell, a plurality of spaced anodes disposed therein, a grid of conducting material mounted opposite each anode, means for moving a series of elements lying on said grids through said cell and means for maintaining these elements in intimate contact with the grid surfaces during such movement.
26. An apparatus for coating roofing elements of the class described comprising an electrolytic cell, a plurality of spaced anodes therein, a grid located opposite each anode and provided with conducting surfaces, means for moving a series of elements provided with conducting surfaces through said cell while being supported on said grids, and means for causing an intimate contact between the conducting surfaces on said elements and said grids.
27. An apparatus for coating roofing elements of the class described comprising an electrolytic cell, a plurality of spaced anodes therein, a grid located opposite each anode and having conducting surfaces formed thereon, means for moving a series of elements supported on said grids through said cell and pressure rollers disposed over said grids and adapted to exert a yielding pressure to force said elements against said grids.
28. An apparatus for coating roofing elements of the class described comprising an electrolytic cell, a plurality of spaced anodes therein, a grid having a plurality of exposed

contact points mounted opposite each anode in spaced relation thereto, means for moving a series of elements lying on said grids through said cell and a pressure roller 5 located opposite each contact point and adapted to exert a yielding pressure to produce an intimate contact between said elements and said contact points.

29. A grid for use in apparatus for coating roofing elements of the class described 10 comprising side bars and cross bars connecting said side bars, said bars being provided

with an insulating casing formed to leave one side of each bar exposed.

30. A grid for use in apparatus for coating roofing elements of the class described 15 comprising side bars and cross bars connecting said side bars, said cross bars being provided with an insulating casing formed to expose said cross bars at a plurality of 20 spaced points.

In testimony whereof I affix my signature.

JULIUS H. GILLIS.
